UNITED STATES PATENT OFFICE.

JOHN HAYWOOD COMPTON, OF NOTTINGHAM, ENGLAND.

CONTROLLING-CIRCUITS OF PALLET-ACTUATING MAGNETS FOR AUTOMATIC ORGANS.

1,312,386.

Specification of Letters Patent.

Patented Aug. 5, 1919.

Application filed December 26, 1916. Serial No. 138,930.

To all whom it may concern:

Be it known that I, JOHN HAYWOOD COMPTON, a subject of the King of Great Britain, residing at Castle Boulevard, Nottingham, Nottinghamshire, England, have invented new and useful Improvements in Controlling - Circuits of Pallet - Actuating Magnets for Automatic Organs, of which the following is a specification.

This invention relates to improvements in the controlling circuits of pallet actuating magnets for automatic organs, and has for its object the provision of electrical means for producing solo and accentuating effects.

This invention provides an arrangement whereby the electric current for operating a note or notes in one department of the organ can be diverted to operate the corresponding note or notes in another department of the organ. In a modified arrangement, the current for operating the selected note or notes, instead of being diverted, is caused to operate such notes in both departments simultaneously.

In the accompanying drawing:—

Figure 1 is a diagram showing electrical connections arranged according to this invention to cause either of two corresponding notes respectively in different departments of an organ to sound alternatively.

Figs. 2 and 3 are diagrams respectively illustrating a modification of the arrangement shown in Fig. 1, and which are herein-after described.

Fig. 4 is a detail view showing the brushes and coöperating conducting bars, which together constitute a tracker bar and portion of a perforated note sheet adapted to pass between said brushes and conducting bars to open and close the electrical circuits.

Referring to Fig. 1 of this drawing: 1 is a conductor extending from a battery *a* or other suitable source of electrical energy, through a pallet actuating magnet 3 of a note in one department of an organ, and through a contact 5 to a switch bar 7. This bar is connected by a conductor 8 to one of a pair of note-playing contacts 9', 9. The other contact of this pair is connected 50 to the battery *a* by a conductor 11, completing a circuit.

The contact devices 9', 9 and 10', 10 in Fig. 1 and their equivalents in Figs. 2 and 3 are shown diagrammatically. The contact device may be advantageously arranged as

shown in Fig. 4, wherein *c* indicates a note sheet formed with perforations *d*, *d* and adapted to pass between brushes 9', 10' and conducting bars 9, 10 mounted on an insulating base *g* and together forming a tracker 60 bar, so that when one of the perforations *d*, *d* comes into register with a brush 9', 10' the corresponding circuit is closed by the brush coming into contact with the bar 9 or 10 through such perforation. 65

A second conductor 2 extends through a pallet actuating magnet 4 of a note of the same pitch as that sounded by energization of the magnet 3, in another department of the organ, and through a contact 6 to the 70 switch bar 7.

The position of the bar 7 with respect to the contacts 5 and 6, is controlled by electromagnets 12, 13 which when energized attract armatures 14, 15, on the bar 7. These 75 electromagnets have their windings 16, 16 connected by a conductor 17. One end of these connected windings is connected to the battery *a* by a conductor 18 and the other end of these windings is connected by 80 a conductor 19 to the conductor 8 at the binding post 20 which also serves to connect the conductor 8 to the switch bar 7. Thus the three circuits, through 3, 4 and 16 are 85 open when the contacts 9', 9 are open.

Another circuit includes a conductor 21, windings 22 only on the electromagnet 12 and additional to the windings 16 thereon, and a conductor 23. For clearness the windings 22 and conductors 21, 23 are shown by 90 broken lines in Fig. 1. This circuit is open at the diverting contacts 10', 10 between the conductor 23 and the conductor 11 connected to the battery *a*.

When the contacts 9', 9 and 10', 10 are 95 open, the switch bar 7 falls by gravity against the magnet 13 and closes the circuit at the contact 5. If the contacts 9', 9 are then closed by the music roll or its equivalent, the bar 7 is held against the electro-magnet 13 with the contacts 5, 7 closed so that the magnet 3 sounds its note. If while the contacts 9', 9 are closed the contacts 10', 10 are also closed by the music roll, the circuit through the magnet 4 will remain open 105 at the contact 6 since the magnet 12, although provided with the windings 22 in addition to the windings 16, is not powerful enough to draw the armature 15 from the magnet 13. 110

If the contacts 10', 10 are closed while the contacts 9', 9 are open, the magnet 12 energized by the windings 22 will attract the armature 14 and close the contacts 6, 7. If the contacts 9', 9 are now closed the magnet 4 will then sound its note but the magnet 13 will not be powerful enough to move the bar 7 to open the contacts 6, 7 so that the contacts 5, 7 will remain open and the magnet 3 will not sound its note. Since the armature is in contact with the poles of the magnet 12, having the two wirings 16, 22, it will be retained in this position even if the contacts 10', 10 are opened, until both contacts 9', 9 and 10', 10 are opened.

In the application of the invention to automatic organs, the contacts 9', 9 and 10', 10 are so arranged and situated that they are opened and closed by the operation of the music roll acting through any convenient device for opening and closing circuit contacts, such as are employed in this type of musical instrument.

The arrangement shown in Fig. 2 is similar in operation to that shown in Fig. 1. In this case the conductor 1^a leads through a pallet actuating magnet 3^a in one department of the organ to contacts 5^a which are closed or opened by a switch bar 24 carried on a rocking arm 25 mounted on a pivot 26, and the circuit is completed through a conductor 28 and note-playing contacts 9^a', 9^a corresponding to the contacts 9', 9 in Fig. 1. Another conductor 2^a leads through a pallet actuating magnet 4^a in another department of the organ to contacts 6^a, 6^a opened or closed by a switch bar 27 on the arm 25, and connected through the contacts 9^a', 9^a to complete the circuit.

The position of the arm 25 is controlled by two electromagnet circuits. One of these circuits is through a conductor 18^a to windings on an electromagnet 13^a, whose armature 15^a is carried on the arm 25, through a conductor 17^a to windings on an electromagnet 12^a, acting to attract the armature 14^a on the arm 25, and through the conductor 19^a and contacts 9^a', 9^a back to the battery *a*.

The other electromagnet circuit is through the conductor 21^a, the windings on an electromagnet 22^a acting to attract the said armature 14^a, and back to the battery *a* through the conductor 23^a and diverting contacts 10^a, 10^a. The arm 25 may carry a weight 29 to return it to the position in which it is shown in Fig. 2, when both pairs of contacts 9^a', 9^a and 10^a', 10^a, are open. By closing the contacts 9^a', 9^a first the circuit through 1^a is energized and by closing the contacts 10^a', 10^a first the circuit through 2^a is energized, but as in the arrangement shown in Fig. 1, when one of these circuits is energized, the other circuit cannot be energized until both pairs of contacts 9^a', 9^a and 10^a', 10^a have been simultaneously opened.

In the further arrangement shown in Fig. 3, one organ department circuit including a pallet actuating magnet 3^b is through the conductor 1^b and the note-playing contacts 9^b, 9^b. The other organ department circuit, 70 including a pallet actuating magnet 4^b, is through the conductor 2^b, contacts 6^b, 6^b, switch bar 27^b, and contacts 9^b', 9^b. One electromagnet circuit is through a conductor 18^b to the electromagnet 13^b attracting the 75 armature 15^b on the arm 25^b pivoted at 26^b and carrying a weight 29^b at one end. This circuit is continued through the conductor 17^b, electromagnet 12^b and contacts 9^b', 9^b back to the battery. The other electromagnet circuit is through the conductor 21^b, 80 electromagnet 22^b attracting the armature 14^b, and the diverting contacts 10^b', 10^b to the battery.

In this case, if the contacts 9^b', 9^b are 85 closed, the circuit 1^b will be energized and sound its note. If the contacts 10^b', 10^b are now closed, this will have no effect since the electromagnet 13^b will prevent movement of the arm 25^b and the contacts 6^b will remain 90 open. If the contacts 10^b', 10^b are closed when the contacts 9^b', 9^b are open, the arm 25^b will be moved to close the contacts 6^b but neither note will be sounded since the circuits through the conductors 1^b and 2^b are 95 open at the contacts 9^b', 9^b. If the contacts 10^b', 10^b are closed, first and then the contacts 9^b', 9^b are closed, both notes will sound simultaneously.

What I claim is:

1. An electric organ having a plurality of departments, electromagnets for operating the pallets of pipes in different departments, and a device for controlling said electromagnets, said device comprising, in combination, electric circuits of which each includes the winding of a pallet operating magnet and a contact device, switch-gear controlling said circuits, said switch-gear normally occupying a position in which one of said circuits is closed and the other circuit is opened, electromagnets for operating said switch-gear, secondary circuits including the windings of said last-named electromagnets for operating said switch-gear, and a contact device in one of the secondary circuits. 100 105 110 115

2. An electric organ having a plurality of departments, electromagnets for operating the pallets of pipes in different departments, 120 and a device for controlling said electromagnets, said device comprising, in combination, electric circuits of which each includes the winding of a pallet operating magnet and a contact device, switch-gear comprising an oscillatory member which when in one of its extreme positions closes one of said circuits and when in its other extreme position closes another of said circuits, said oscillatory member normally oc- 125 130

cupying one of its extreme positions, electromagnets for operating said switch-gear, secondary circuits including the windings of said last-named electromagnets for operating said switch-gear, and a contact device in one of the secondary circuits.

3. An electric organ having a plurality of departments, electromagnets for operating the pallets of pipes in different departments, and a device for controlling said electromagnets, said device comprising, in combination, a main electric circuit including a source of electric energy, electric circuits which are branched from said main circuit and of which each includes the winding of a pallet operating magnet, a multiple-way switch controlling said branch circuits, said switch having a movable member normally occupying a position in which it closes one of said branch circuits and opens the other branch circuit, a contact device in said main circuit, electromagnets for operating said movable member, secondary branch circuits including the windings of said last-named electromagnets for controlling the position of said movable switch-member, and a contact device in one of said secondary branch circuits.

4. An electric organ having a plurality of departments, electromagnets for operating the pallets of pipes in different departments, and a device for controlling the said electromagnets, said device comprising, in combination, a main electric circuit including a source of electric energy, electric circuits which are branched from said main circuit and of which each includes the winding of a pallet operating magnet, a two-way switch comprising an oscillatory switch-arm which normally stands in the position in which it closes one of said branch circuits and opens the other branch circuit, a contact device in said main circuit, electromagnets for operating said switch-arm in opposite directions, a secondary branch circuit including windings on both switch operating electromagnets, and a secondary branch circuit including windings on one of said switch-

actuating electromagnets and a contact device.

5. An electric organ having a plurality of departments, electromagnets for operating the pallets of pipes in different departments, and a device for controlling the said electromagnets, said device comprising, in combination, a main electric circuit including a source of electric energy, electric circuits which are branched from said main circuit and of which each includes the winding of a pallet-operating magnet, a two-way switch comprising an oscillatory switch-arm which normally stands in the position in which it closes one of said branch circuits and opens the other branch circuit, a contact device in said main circuit, an electromagnet adapted to move the switch-arm out of its normal position, a second electromagnet adapted to retain the switch-arm in its normal position, a secondary branch circuit including windings on both of said switch-operating electromagnets, and a secondary branch circuit including windings on the electromagnet for moving the switch-arm out of its normal position and also including a contact device.

6. An electric organ having a plurality of departments, electromagnets for operating the pallets of pipes in different departments, and a device for controlling said electromagnets, said device comprising, in combination, alternative electric circuits of which each includes the winding of a pallet-operating magnet and a contact device, a switch whereby one of said circuits can be closed at a time, means for normally holding said switch in a position in which it closes one of said circuits and opens the other circuit, and an additional electric circuit including a contact device and an electromagnet adapted to move said switch out of its normal position into one in which the other alternative circuit is closed and the one normally closed is open.
